UNITED STATES PATENT OFFICE.

HORTENSE T. IGELSTROM, OF NEW YORK, N. Y.

PIN-CLASP.

SPECIFICATION forming part of Letters Patent No. 715,808, dated December 16, 1902.

Application filed May 2, 1902. Serial No. 105,607. (No model.)

To all whom it may concern:

Be it known that I, HORTENSE T. IGELSTROM, a citizen of the United States, and a resident of New York, in the county of New York and State of New York, have invented certain new and useful Improvements in Pin-Clasps, of which the following in a specification.

My invention relates to a fastening device or pin-clasp designed more especially for use in fastening dress-shields into the sleeves of ladies' garments, but may be used for other purposes; and the invention consists, namely, in the article constructed with a pair of pointed hooks, combined with clasp and guard arranged to shield the points of the hooks and hold the clasp closed.

The invention also consists in the construction, arrangement, and combination of parts, all as hereinafter described and claimed.

In the accompanying drawings, to which reference is made and form a part of this specification, Figure 1 is a front elevation of a dress-shield and a portion of a garment having a pair of my new fastening-clasps applied thereto. Fig. 2 is an enlarged front elevation of the clasp. Fig. 3 is an enlarged side view of the clasp. Fig. 4 is a view of the back of the clasp with the pointed hooks lifted or turned up in position ready for applying the clasp. Fig. 5 is a back view closed. Fig. 6 shows a modified form of the pointed hooks.

In the drawings, 2 designates a dress-shield, 3 the armpit portion of a lady's dress, and 4 4 designate a pair of my new fastening-clasps applied for securing the shield to the garment. Each clasp comprises the two sharp-pointed hooks 5 5, substantially of the form shown, and each preferably formed integral with a bar 6. On this bar 6 is hinged the guard 7 for the points of the hooks and a clasp-plate 8 for holding the dress-shield and seam of the dress or other objects in the hooks and for holding the guard over the points of the hooks. The guard 7 and clasp-plate 8 are by preference made integral of a single piece of metal or other suitable material folded upon or around the bar 6, so as to form the hinge-eye or sleeve 9. The said hinge-eye or sleeve is by preference open at one side, so that the bar of the hooks may be

slipped or sprung into place, and if made of metal no additional fastening is required save the spring action of the clasp and guard. The guard 7 is by preference formed with 55 small pockets or depressions 10, set back to avoid dulling the points of the hooks from contact therewith. The edges of the clasp-plate 8, when the clasp is closed, spring in between the pointed ends of the hooks, which 60 hooks by their spring action hold the clasp in closed position. For this purpose the extremities of the spring-hooks normally stand a distance apart somewhat less than the width of the clasp, and it is advisable to slightly bend 65 back the clasp, as shown at 13, so that the edges of the clasp at its points of contact with the hooks will fall well between the hooks, and to effect a still firmer hold it is advisable to curve slightly inward the points of the 70 hooks, as shown at 14, or for this purpose the material of the hooks may be slightly flattened to form inward bulges.

The lower edge of the clasp 8 projects below the lower edge of the guard 7 to form a 75 thumb-piece 15 to facilitate the opening of the clasp, and for this purpose also I shall in some cases form or provide one of the pointed hooks with a lateral projection 16, so that by pressing back on this the clasp may be readily opened.

Having thus described my invention, what I claim as new, and desire to secure by Letters Patent, is—

1. A pin-clasp comprising a pair of pointed 85 hooks or pins, a bar to which said hooks or pins are connected, a clasp-plate hinged to said bar, a guard-plate integral with said clasp-plate, a hinge-eye or sleeve for said bar formed by the clasp-plate and the guard-plate, 90 the said hooks or pins being constructed to hold the clasp in closed position and to hold portions of the guard-plate in front of the points of the said hooks or pins, substantially as described.

2. In a pin-clasp, a clasp-plate and a guard-plate made of one piece of metal, a hinge-eye or sleeve formed by said clasp-plate and guard-plate, the corners of the guard-plate being extended beyond the adjacent edge of the clasp-plate and said extended portions being formed 100 with depressions in combination with a bar

held in said hinge-eye or sleeve, and a pair of bent hooks or pins connected to said bar, substantially as described.

3. A pin-clasp comprising a pair of pointed hooks or pins, a bar to which said pointed hooks or pins are connected, the said hooks or pins having inward bends 14, in combination with a clasp-plate adapted to spring between said bends and a guard to cover the points of the said pointed hooks or pins, the clasp-plate and guard being hinged to the said bar, substantially as described.

4. In a pin-clasp, the pointed hooks or pins 5, 5, a bar 6, to which said pins or hooks are connected, the said hooks or pins being provided with inward bends 14, in combination

with a clasp-plate hinged to the said bar and adapted to spring between the said bends, substantially as described.

5. In a pin-clasp a pair of pointed hooks 20 connected to a bar, the points being formed with inward bends, one of said hooks being provided with a projection to facilitate opening the hooks, combined with a guard-plate adapted to be held in closed position by the 25 said inward bends of the pointed hooks substantially as described.
